LEBOY J. BUTTOLPH, OF GRANTWOOD, NEW JERSEY, ASSIGNOR TO COOPER HEWITT ELECTRIC COMPANY, OF HOBOKEN, NEW JERSEY, A CORPORATION OF NEW JERSEY.

HIGH-INTENSITY INDUCTION LAMP.

Application filed July 1, 1926. Serial No. 119,921.

The present invention relates to electric lamps in which a gas or vapor is brought to luminescence by inducing therein the flow of a high frequency alternating current. The 5 invention relates more particularly to lamps of this type in which a high intensity discharge is produced. It further relates to means for aiding in the starting of a lamp of this type. The invention also relates to 10 an induction lamp for producing ultra violet light of high intensity and concentrations adapted for easy manipulation and for the application of high intensity light to localized areas for use in the therapeutic field and 15 in the arts generally.

Various other objects and advantages of the invention will be obvious from the following particular description of forms of apparatus embodying the invention or from an 20 inspection of the accompanying drawings; and the invention also consists in certain new and novel features of construction and combinations of parts hereinafter set forth and claimed.

25 In the following description and in the claims parts will be identified by specific names for convenience, but they are intended to be as generic in their application to similar parts as the art will permit.

30 In the accompanying drawings I have shown for purposes of illustration one form of apparatus with certain modifications thereof embodying the invention, in which

Fig. 1 is an elevation view in part section 35 of a vapor lamp having a gas enclosing envelope in the form of a pair of bulbs connected by a constricted tube about which is mounted a high frequency induction coil of comparatively small diameter, and a light applicator in operative relation to a particular window portion of the lamp,

Fig. 2 is an elevation view of a similar device with a water cooled applicator,

Fig. 3 is a sectional view taken along the 45 line 3—3 of Fig. 2,

Fig. 4 is a diagrammatic view in elevation showing a single bulb lamp.

In Figs. 1, 2 and 3 of the drawings the envelope 1 which is of glass, quartz or the like 50 is in the form of two bulbs 3 and 4 which are connected by the short tube 6. Positioned transversely in tube 6 is the broken ring 8 which is held in position by the lugs or annular corrugations 9 formed on the inner sur-

face of said tube 6. Extending inwardly 55 from a place on bulb 4 diametrically opposite tube 6 and to within a short distance of the tube 6 is the re-entrant tube 10 which carries at its inner end the window 12. This unit 12 is formed of glass, quartz or the like 60 in accordance with the nature of the light desired to be transmitted therethrough. In the envelope is a quantity of mercury 13. The high frequency coil 15 has connected in series therewith the condenser 16 and across the 65 tube is the spark gap 18, the leads 20 serving for connection to a suitable source of high voltage alternating current not shown. The rod 21 of quartz or glass serves as a light 70 applicator in that it transmits light rays 75 from the inner or receiving end to the other or dispensing end, as is now well known in therapy, and is movable into tube 10 and into close proximity to window 12 in accordance with operating conditions and with the intensity of light desired to be applied. In Fig. 2 is shown diagrammatically a water cooled light filter 22 of the well known type mounted to the light applicator 21'. The tubes 23 and 24 serve to carry cooling fluid to and from 80 the cell of the filter to remove heat absorbed from the light by the fluid of the filter.

The modification shown in Fig. 4 has an envelope which comprises a bulb 30 which carries a short tube 31 which connects therewith and which in turn carries at its outer end a window 33 of quartz or other light transmitting material. In the envelope near the inner end of the tube 31 is mounted the broken ring 35 similar to ring 8 of Figs. 1 to 3. The 90 high frequency coil 36 positioned about tube 31 is connected to a high frequency circuit comprising a high voltage generator 38, the spark gap 39 and the condenser 40. A filling of a gas or vapor is supplied in the envelope such as neon, argon, mercury or any 95 other suitable gas or mixtures of gases.

In the use of the apparatus of this invention the high frequency coils 15 or 36 are energized in a manner well known in the art 100 to induce a current flow in the gas or vapor of the lamp envelope to bring about a radiant discharge therefrom. The broken ring 8 or 35 serves to aid in the starting of the discharge by having induced therein a current 105 flow which passes from one end of the ring to the other and jumps the space between the two ends and forms a spark thereat which

energizes the gas or vapor and brings it up to current flow and discharge supporting condition. The tube 6 or 31 and the coils 15 or 36 being of small diameter, a comparatively high intensity of discharge will be supported in these tubes, that is, light emission will take place substantially throughout the lamp envelope but on account of the high intensity magnetic currents close to the energizing coils the light will be of a comparatively high intensity in these tubes. The enlarged portions or bulbs 3, 4 and 30 are necessary to provide sufficient space distance for electronic movement in the envelope to attain sufficient acceleration to bring about radiation producing conditions and to provide cooling area for the lamp for securing proper operating pressures therein. The windows 12 and 33 are positioned close to the high intensity light produced within or at the tubes 6 or 31 to secure an efficient light transmission from the high intensity space. This close positioning to the high intensity spot in the lamp has the further advantage of avoiding clouding of the window by condensation of vapor thereon when material such as mercury is used because the high temperature at this point will prevent such condensation.

It is to be understood that when desired the ring 8 or 35 is dispensed with and starting and operating of the lamp attained solely through the direct effect of the magnetic currents upon the vapor or gas in the envelope. It is further to be understood that instead of a broken ring a closed coil of one or more turns may be used in accordance with the invention set forth in my copending application Serial Number 105,951 filed May 1, 1926.

While I have shown and described and have pointed out in the annexed claims certain novel features of the invention, it will be understood that various omissions, substitutions and changes in the forms and details of the device illustrated and in its operation may be made by those skilled in the art without departing from the spirit of the invention.

I claim—

- 50 1. In a vapor electric lamp of the induction type, a sealed envelope having a discharge supporting gas or vapor therein, said envelope having a constricted portion adapted for the application of the high frequency induction coil, and a ring of electrically conducting material positioned within the constricted portion of the envelope.
- 55 2. In a vapor electric lamp of the induction type, a sealed envelope having a transparent window and a discharge supporting

gas or vapor therein, said envelope having a constricted portion adapted for the application of a high frequency induction coil, said window being located in the high temperature area and adjacent said constricted opening.

3. In a vapor electric lamp of the induction type, a sealed envelope having a transparent window, a discharge supporting gas or vapor therein, said envelope having a constricted portion adapted for the application of the high frequency induction coil, and a ring of electrically conducting material positioned within the constricted portion of the envelope.

4. In a vapor electric lamp of the induction type, a sealed envelope having a transparent reentrant window and a discharge supporting gas or vapor therein, said envelope having a constricted portion adapted for the application of a high frequency induction coil, said transparent window being positioned in close proximity to said constricted portion of the envelope.

5. In a vapor electric lamp of the induction type, in combination a sealed envelope comprising two enlarged portions joined by a constricted passage, a transparent reentrant window formed in the wall of the envelope having said constricted passageway, and a filling of a discharge supporting gas or vapor in the envelope.

6. In a vapor electric lamp of the induction type, a sealed envelope of vitreous material in the form of two bulbs joined by a constricted passageway, a re-entrant tube extending inwardly from the wall of one of said bulbs to within a short distance of said constricted passageway and carrying at its inner end a transparent window, a discharge supporting gas or vapor in the envelope, and a coil of electrically conducting material positioned in said constricted passageway and having its ends terminating close to each other.

7. In a vapor electric lamp of the induction type, a sealed envelope of quartz like material in the form of two connecting bulbs joined by a strictured passageway, a broken ring positioned in said strictured passageway transversely thereof, and having its ends terminating within a short distance of each other, said envelope having a portion transparent to ultra violet light, and a quantity of mercury in said envelope.

Signed at Hoboken in the county of Hudson and State of New Jersey this 25th day of June, A. D. 1926.

LEROY J. BUTTOLPH.
